UNITED STATES PATENT OFFICE

PAUL SAPIENZA, OF DETROIT, MICHIGAN

INTERNAL-COMBUSTION ENGINE

Application filed March 21, 1927. Serial No. 176,961.

This invention relates to improvements in internal combustion engines, and refers more particularly to two stroke engines.

It is an object of the invention to provide an engine having a cylinder with a piston therein, a rod from the latter extending through one end of the cylinder, and a plunger in the cylinder having a cam actuated rod extending through the opposite end of the cylinder.

Another object of the invention is to provide an internal combustion engine having a plunger in its cylinder as well as the usual piston, a plunger rod which extends through the opposite end of the cylinder to the piston rod, and to so move the plunger that it assists in expelling burnt gas from the cylinder, and also draws fresh gas into the latter.

A further object of the invention is to provide an internal combustion engine having an arrangement of cams whereby the plunger is reciprocated in the cylinder, and other cams by which gas is admitted into the cylinder and allowed to pass through the plunger to a space between it and the piston, at certain times during each double stroke of the piston.

With these and other objects in view which will become apparent as the specification proceeds, the invention is hereinafter more fully described with the aid of the accompanying drawings, in which:

Figure 1 illustrates a side elevation of the invention partly in section.

Figure 2 is a plan view.

Figure 3 is a section on the line 3—3 of Figure 1, and

Figure 4 is a diagram showing the movement imparted by two of the cams to the plunger rod and to a valve positioned therein.

Referring to the drawings, 1 designates a cylinder open at its lower end and closed at its upper end by a wall 2. In the cylinder there is a piston 3 having a connecting rod 4 attached thereto by a wrist pin 5. The opposite end of the connecting rod is mounted on a crank shaft 6.

In the cylinder 1 there is a plunger 7 having a rod 8, usually integral with it, which

projects through an aperture 9 in the wall 2, through which said rod is a good sliding fit. Axially through the rod 8 and plunger 7 is an opening 10 which is tapered outwardly on the underside of the plunger at 15 to 55 form a seat for a valve 11. The stem 12 of this valve extends upwards through the opening 10 and at its upper end a fork 13, in which a roller 14 is rotatably held, is mounted thereon. In the opening 10 and preferably in proximity to the valve seat 15 is an internal flange 16 integral with the plunger 7, which forms a guide for the rod 8 and also acts as a stop for the lower end of the coil spring 17 which is arranged around the said 60 rod. The upper end of the spring 17 rests against the lower portion 13a of the fork 13. The upper end of the opening 10 is multi-sided internally as also is the lower portion 13a of the yoke which fits thereto. In this 65 manner the yoke is permitted axial movement in the rod but is held against rotation, so that the roller 14 remains in such position that it will freely rotate against the underside of the cam 37 as the latter turns. Extending substantially at right angles from the side of the rod 8 are two pins 30 one above the other; on each pin is a roller 31 rotatably mounted thereon. On the cylinder wall 2 are guides 50 against which the slides 51 rest, 70 and usually integral with, the upper end of the rod 8 are slidably mounted, so that when the said rod moves up and down as the cam 37 turns between the rollers 31, the said rod is held against rotary movement. 75

On the wall 2 towards one side, and usually integral therewith, is a tubular housing 19, the passage 27 through which terminates at its lower end in a smaller passage 20, which latter extends through the wall 2 and opens into the upper end of the cylinder. The underside of the passage 20 is tapered outwardly at 21 to form a seat for the valve 22, and the stem 23 of the valve extends upwards through the passages 20 and 27 and has a fork 24 mounted at its upper end which carries a roller 25. The passage 20 should be somewhat larger than the spindle 23 for reasons hereinafter stated. A spring 26 around the valve stem 23 rests at its lower end against the shoulder 90 95 100

formed at the lower end of the passage 27 and bears at its upper end against an enlarged lower portion 28 of the fork 24 into which the upper end of the stem 23 is generally threaded. The upper end of the passage 27 is 5 multi-sided as also is the enlarged lower portion 28 of the fork 24, so that the latter cannot turn in the said passage although it is permitted axial movement therein.

10 The crank shaft 6 is supported as by bearings 32, and has a bevel gear 33 thereon which meshes with a bevel gear 34 on the shaft 35, which latter is supported as by bearings 35^a. On the shaft 35 a wheel 36 is so mounted as to 15 rotate therewith. This wheel has two external cams 37 and 38 thereon, and one internal cam 39. The underside of the cam 37 adjacent to its periphery rides on the roller 14, so that the depressed portion 37^a of the cam 20 forces the valve 11 downwards. That portion of the cam 38 adjacent to its periphery travels around between the rollers 31 so that its depressed portion 38^a imparts a reciprocating movement to the rod 8 and the plunger 7. 25 The internal cam 39, usually integral with the rim of the wheel 36 and connected to the hub 40 as by spokes 41 bears against the roller 25 and controls the operation of the valve 22.

30 45 designates an inlet into the passage 20, which is of such size in proportion to the valve stem 23 that when the valve 22 moves downwards off its seat there is sufficient room for combustible mixture to pass from the inlet 35 into the upper end of the cylinder 1. 42 denotes a passage from the upper side of the plunger 7 into the opening 10 and below the internal flange 16, so placed that when the valve 11 is off its seat 15 combustible mixture 40 passes into that portion of the cylinder between the plunger 7 and the piston 3. 43 indicates a spark plug arranged through the side of the cylinder towards its upper end, and 44 is an exhaust port through the side of the 45 cylinder towards its lower end.

The operation of the engine is as follows: When gas is exploded in the cylinder between the piston 3 and the plunger 7 the former moves downwards into the position shown at 50 3^a; when the piston is towards the bottom of its stroke the cam 38 moves the plunger 7 downwards thereby expelling burnt gas through the exhaust port 44. Meanwhile the cam 39 forces the valve 22 off its seat so that 55 gas is drawn into the top of the cylinder; on the return stroke of the plunger the valve 11 is opened by the cam 37 as soon as the piston has risen sufficiently to close the exhaust port 44. Compression occurs on the upstroke of the 60 plunger and piston both above and below the plunger. It will be noted that when the latter is in top position there is only bare clearance space between the wall 2 and the plunger so that practically the whole of the charge 65 must pass to the underside where it is fired.

The movement of the plunger 7 and valve 11 in the cylinder can be clearly seen from the cam diagram shown in Figure 4.

While in the foregoing the preferred embodiment of the invention has been described and shown, it is understood that the construction is susceptible to such modifications as fall within the scope of the appended claims.

What I claim is:

1. In an internal combustion engine, the combination of a cylinder having one end open and a piston and a plunger therein, a connecting rod pivotally secured to said piston and extending through the open end of said cylinder, the closed end of said cylinder having a substantially central passage therethrough, another rod on said plunger extending through said passage, said other rod and plunger having a substantially axial opening therethrough, a plunger valve adapted to seat at the plunger end of said opening, a stem on said valve extending into said opening, said plunger rod having a substantially radial opening therein connecting the substantially axial opening with the interior of the cylinder above the plunger, a spark plug extending into said cylinder towards its closed end, said cylinder having an exhaust port towards its open end and an inlet port in its closed end, a valve controlling the inlet port, a cam adapted to reciprocate said plunger rod and plunger, a second cam adapted to move said plunger valve off its seat, a third cam adapted to move said inlet valve off its seat and means for rotating said cams.

2. In an internal combustion engine, the combination of a cylinder having a piston and a plunger therein, a rod secured to said piston and extending through one end of said cylinder, a shaft rotated by the movement of said rod, a wall at the other end of the cylinder having a passage therethrough, another rod on said plunger extending through said passage, said rod and said plunger having an opening therethrough, said rod having a second and substantially radial opening connecting said first named opening with the interior of the cylinder above the plunger, a valve adapted to seat at the plunger end of said first opening, a valve stem on said valve extending into said first opening, a roller revolvably mounted on the upper end of said valve stem, other rollers revolvably mounted on the side of said plunger rod, a spark plug extending into said cylinder, said cylinder having an inlet port thereinto, an inlet valve adapted to close said inlet port, a cam adapted to rotate over said first roller and impart movement to said valve stem, a cam adapted to rotate with its periphery between said other rollers and reciprocate said plunger rod, a cam adapted to move said in-

let valve off its seat, and means for rotating said cams when said shaft turns.

3. In an internal combustion engine, the combination as described in claim 2 wherein means are provided for holding said plunger rod against rotary movement.

4. In an internal combustion engine, the combination as described in claim 2 wherein means are provided for holding the valve stem against rotary movement.

5. In an internal combustion engine, the combination of a cylinder having a piston and a plunger therein, a rod connected to said piston, a shaft adapted to be rotated by said rod, a closed end on said cylinder having a passage therethrough, a rod on said plunger extending through said passage, a substantially axial opening through said plunger and its rod, a valve adapted to seat against the plunger end of said opening, a substantially radial passage through said plunger rod from said first named opening into that portion of the cylinder above the plunger, guides on the closed ends of the cylinder, slides on said plunger rod adapted to move vertically in said guides, a roller mounted on the upper end of the valve stem, two rollers revolvably mounted on one side of the plunger rod, a tubular housing on the closed end of the cylinder opening into the latter, said closed cylinder end having an inlet port therein opening into said tubular housing, an inlet valve adapted to seat against the cylinder end of said tubular housing, a stem on said inlet valve extending into said housing, a roller mounted on the upper end of said latter valve stem, a cam adapted to rotate against said first named roller and move said first valve off its seat, a cam adapted to rotate with its periphery between said rollers mounted on the side of the plunger rod and to reciprocate said plunger and rod, a cam adapted to move said inlet valve off its seat, independent means for tending to hold each valve on its seat, independent means for holding each valve stem against rotation, means for turning said cams when said shaft rotates, a spark plug extending into said cylinder, and said cylinder having an exhaust port therefrom.

6. In an internal combustion engine, the combination of a cylinder having a closed end with a passage therethrough, a piston and a plunger in said cylinder, a rod connected to said piston extending through one end of said cylinder, a shaft rotated by the movement of said rod, a rod from said plunger extending through said passage, guide rollers extending laterally from said plunger rod, a cam having part of its periphery between said guide rollers adapted to reciprocate said plunger in said cylinder, said closed cylinder end having an intake port therein, a valve adapted to control said intake port opening, a cam adapted to move said valve, said plunger

having a passage therethrough, another valve adapted to control the opening of said plunger passage, another cam adapted to move said other valve, and means for moving said cams when said shaft rotates.

7. In an internal combustion engine, the combination as described in claim 6 wherein a second shaft is driven from the shaft named therein, a wheel fixed on the second shaft, the cams which operate the plunger and the valve in the plunger opening respectively being located on the periphery of said wheel, and the cam which operates the inlet valve also on said wheel.

8. An internal combustion engine having a pair of radially spaced apart intake valves, a wheel driven by the engine provided with a pair of stepped circumferentially extending cams, one cam engaging one valve and the other cam engaging the other valve to open said valves upon rotation of the wheel.

9. An internal combustion engine having a pair of intake valves, a wheel driven by the engine, said wheel provided with an internal circumferentially extending cam engaging one valve and an external circumferentially extending cam engaging the other valve to actuate said valves successively upon rotation of the wheel to admit each charge successively through said valve openings.

10. An internal combustion engine having a cylinder provided with an intake opening, a valve controlling said opening, a working plunger in the cylinder, said plunger having an intake opening, a valve controlling the opening in the plunger, a cam wheel driven by the engine, said wheel provided with an internal cam engaging one valve and an external cam engaging the other valve to actuate said valves upon rotation of the wheel.

11. An internal combustion engine having a cylinder provided with an intake opening, a valve controlling said opening, a plunger reciprocally mounted in the cylinder, said plunger provided with an intake opening, a cam wheel driven by the engine, a plunger valve controlling said opening, said wheel provided with internal and external cams, one cam engaging the first mentioned valve and the other cam engaging the second mentioned valve, to open said valves successively upon rotation of the wheel.

12. An internal combustion engine having a cylinder provided with an intake opening, a valve controlling said opening, a plunger reciprocally mounted in the cylinder, said plunger provided with an intake opening, a cam wheel driven by the engine, said wheel provided with a plurality of circumferentially extending cams spaced axially about the wheel, one cam engaging the intake valve in the cylinder to open said valve, a second valve engaging the plunger to actuate the plunger, and a third cam engaging the valve

controlling the opening in the plunger to open said valve.

13. An internal combustion engine having, in combination, a power cylinder and piston 5 in one end of the cylinder, a plunger in the opposite end of the cylinder said cylinder provided with an intake opening at its plunger end, said plunger provided with an intake opening, a valve controlling each opening, a 10 cam wheel driven by the power piston and provided with a pair of cams arranged circumferentially thereabout and adapted to engage said valves to open them successively to admit a charge into the end of the cylinder beyond the plunger and then into the cylinder 15 through the plunger.

14. An internal combustion engine comprising, in combination, a power cylinder and piston, a plurality of longitudinally operable 20 radially spaced apart valves arranged within the cylinder, a cam wheel driven by the power piston provided with a plurality of circumferentially arranged radially and axially stepped cams engaging said valves to actuate 25 them in a determined timed order of succession.

15. An internal combustion engine comprising, in combination, a cylinder having an intake opening, a piston positioned within the 30 cylinder, a plunger positioned within the cylinder opposed to the piston, said plunger provided with an intake opening, a valve controlling the intake opening into the cylinder, a valve controlling the intake opening through 35 the plunger, a rotatably supported cam wheel driven by the piston, said cam wheel provided with two circumferentially arranged cams one engaging each valve to open said valves.

16. An internal combustion engine comprising, in combination, a cylinder having an intake opening, a piston positioned within the cylinder, a plunger positioned within the cylinder opposed to the piston, said plunger provided with an intake opening, a pair of 45 valves one controlling each intake opening, a crank shaft extending at right angle to the axis of the cylinder and coupled with the piston to be driven thereby, a cam shaft extending substantially parallel to the axis of the 50 cylinder and coupled with the crank shaft to be driven thereby, a cam wheel carried by the cam shaft and provided with a pair of circumferentially arranged cams one engaging one valve and the other engaging the other 55 valve to open said valve.

17. An internal combustion engine comprising, in combination, a cylinder having an intake opening, a piston positioned within the cylinder, a plunger positioned within the cylinder opposed to the piston, said plunger provided with an intake opening, a pair of valves one controlling each intake opening, a crank shaft extending at right angle to the axis of the cylinder and coupled with the piston to be 60 driven thereby, a cam shaft extending sub- 65

stantially parallel to the axis of the cylinder and coupled with the crank shaft to be driven thereby, a cam wheel carried by the cam shaft and provided with a pair of circumferentially arranged cams one engaging one valve and the other engaging the other valve to open the valves controlling said openings in succession in the reverse order to that in which the openings are herein enumerated.

18. An internal combustion engine having 75 a cylinder, a piston in the cylinder, a pair of intake openings to admit a charge into the cylinder, each intake opening provided with a control valve, a crank shaft coupled with the piston to be rotated thereby, a cam shaft arranged at a right angle to the crank shaft and substantially parallel to the axis of the cylinder, a cam wheel carried by said cam shaft overhanging one end of the cylinder and provided with a pair of circumferentially 80 arranged cams one engaging one valve and the other engaging the other valve to open said valve successively to admit a charge into the cylinder.
